By James L. Morris.

Attest,

UNITED STATES PATENT OFFICE.

BARTHolemew J. MURPHY, OF MIDDLETOWN, CONNECTICUT.

SLED-PROPELLER.

SPECIFICATION forming part of Letters Patent No. 371,897, dated October 18, 1887.

Application filed July 23, 1887. Serial No. 245,121. (No model.)

To all whom it may concern:

Be it known that I, BARTHolemew J. MURPHY, a citizen of the United States, residing at Middletown, in the county of Middlesex and State of Connecticut, have invented new and useful Improvements in Propelling and Controlling Attachments for Sleds, of which the following is a specification.

The present invention has for its object to provide a propelling and controlling attachment for hand-sleds which is simple in construction, easily applied in position, effective in operation, and not liable to get out of order.

15 The invention consists in the features of construction and combination of devices, hereinafter described and claimed, reference being made to the accompanying drawings, illustrating my invention, in which—

20 Figure 1 is a side elevation of a hand sled, showing the propelling and controlling attachment in position for operation. Fig. 2 is a plan or top view of the same. Fig. 3 is a side elevation showing the parts thrown out 25 of action.

The reference - numeral 1 designates the frame of a hand or coasting sled, which is of the usual or any approved construction. To the front and rear vertical knees at each side 30 of the sled is secured a longitudinal slotted bar, 2, in which moves or plays a vertical propelling and controlling lever, 3. This lever is shod with a metal point, 4, and is pivoted centrally, or nearly so, between its 35 ends to one end of a horizontal arm, 5, which extends in a forward direction from the rear knee of the sled-frame. The arm 5 is connected with said knee by means of a pivot-pin, 6, so that it will be free to rise and fall 40 in a plane at right angles to the sled-seat as the lever 3 is moved forward or backward.

It will be understood that the parts above mentioned are present at each side of the sled, as is shown in Fig. 2.

45 In order to propel the sled by the devices applied thereto in the above-described manner, the rider pushes forward the levers 3, causing the shoe, or pointed portions thereof, to move backward and engage with the ground, 50 thereby propelling the sled in a forward di-

rection. As shown in dotted lines in Fig. 1, the levers, when drawn backward, take hold upon the ground, and when they are pushed forward they make the propelling-stroke. When both levers are pressed backward, the 55 points thereon enter or engage with the ground and the motion of the sled is arrested, and when either one of such levers is moved the sled is steered or moved to the right or left, as will readily be apparent.

The provision of the pivoted arms will allow the levers to be properly manipulated, since such arms are free to rise and fall as the levers are moved forward or backward. The slotted or grooved guides in which the levers move 65 are essential features of my invention, since they prevent the lateral movement of said levers and properly guide the same during their backward and forward play.

When the sled is not in use or the attachment is not required for use, the levers are turned into or upon the pivoted arms and the front portions of the levers caused to rest upon horizontal pins or stops 12 at the front of the sled-frame, as is shown in Fig. 3.

I am aware that lever propelling and brake devices have heretofore been applied to hand-sleds, as in Letters Patent No. 157,823; but the construction and arrangement are not the same as mine.

Having thus described my invention, what I claim is—

The combination, with a sled having front and rear knees supporting the seat, of horizontal arms 5, pivoted at their rear ends on 85 the rear knees to rise and fall at their front ends in a plane at right angles to and below the seat, the longitudinal slotted guides 2, secured to the knees below the sled-seat, and propelling hand-levers pivoted intermediate 90 their ends directly to the rising and falling front ends of the horizontal arms beneath the sled-seat, substantially as described.

In testimony whereof I affix my signature in presence of two witnesses.

BARTHolemew J. MURPHY.
